CLAIM

(57) The ornamental design for a battery and charger assembly as shown and described.

DESCRIPTION

FIG. 1 is a perspective view of a battery and charger assembly according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings are for the purpose of illustrating portions of the battery and charger assembly that form no part of the claimed design.
